BY *Meyer & Coranagh*

ATTORNEYS

UNITED STATES PATENT OFFICE.

PETER H. MARGULIS, OF NEW YORK, N. Y.

OVERSHOE.

Application filed May 17, 1923. Serial No. 639,564.

My invention relates to improved overshoes and methods of making the same.

The general object of the invention is to provide overshoe structures, of the class generally designated as rubber overshoes, which fit or co-operate with the shoe of the user in such a way that accidental displacement of the overshoe is substantially or entirely prevented; to provide a snug and neat fit and at the same time to provide for easy application and removal of the overshoe.

A more particular object is to provide heelless overshoe structures in which the parts around the heel opening are so designed as to closely fit the innershoe and exclude dirt and water, and the rear or counter portions of the overshoe are especially devised to fit and co-operate with the innershoe to effectively prevent accidental displacement or downward slipping of the overshoe counter.

Another object is to provide a lined overshoe-upper structure in which the lining terminates at a point forward of the rear end of the rubber counter portion so that the forward part of the upper, including side portions of the counter, are properly strengthened and reinforced by lining, but the rear end of the counter is flexible or elastic, which permits the overshoe to be more easily applied, causes it to conform closely and flexibly to the inner shoe when applied, and the rear counter structure is preferably, moreover, normally conformed or depressed so that it exerts an additional tension on the back of the shoe counter which holds the overshoe in place, prevents downward or upward slipping at the heel, and simultaneously draws the overshoe 40 shank firmly up in contact with the shoe shank and back against the front of the shoe heel. These features are especially desirable in a heelless overshoe although they are equally advantageous and may be incorporated in heeled overshoes.

Another object is to provide a heelless overshoe having a heel opening, the margin of the upper structure adjacent to the heel opening being suitably reinforced by a fabric lining which preferably extends toward the rear end of the opening but does not extend entirely around the back of the heel opening; and moreover to thicken and reinforce the upper structure at the heel opening, and more especially to give to the

margin of the upper at the heel opening an inward curvature or bend and to provide this margin with an angular or sharp edge which fits closely in the joint or crevice between the shoe counter and heel base to effectively exclude dirt and moisture and prevent downward slipping of the overshoe counter.

Another important object is to so devise the overshoe construction that it is capable of being produced by an improved process or method, and to provide such an improved process or method of construction including as briefly described, the formation of the upper rubber structure of the overshoe substantially in one operation or in a single piece or else to form in a single operation or in a single piece the rear portion of the rubber overshoe structure in which most of the novel features of construction are embodied, for the purposes above and hereafter stated.

The process is desirably devised so that the entire rubber portion of the overshoe upper, or the rear portion or counter thereof, may be produced in one operation of suitable forming rolls or dies.

Another object of the invention is to provide a structure and a process by which the overshoe may be readily and advantageously built up on a last in an improved and advantageous manner.

The characteristics and advantages of the invention are further sufficiently explained in connection with the following detail description of the accompanying drawings, which show certain representative embodiments of the invention and also sufficiently explain representative performances of the process of manufacture. After considering these examples, persons skilled in the art will understand that many variations may be made within the principles of the invention, and I do not limit myself to details except as claimed hereafter.

Figure 1 is an outside plan view of the rubber rear portion or overshoe counter, substantially as originally produced in the "flat," embodying the invention in one form.

Figure 2 is an inside plan view of the same.

Figure 3 is a section at 3—3 of Figure 1.

Figure 4 is a section at 4—4 of Figure 1.

Figure 5 shows a suitable front or vamp portion of an overshoe upper adapted to co-

operate with the counter shown in previous figures and applied to a suitable upper lining.

Figure 6 shows the combined lining and 5 vamp applied to or formed about a suitable last.

Figure 7 shows in full lines the complete overshoe structure in normal shape, and in dotted lines, its shape when applied to a 10 shoe.

Figure 8 shows the same overshoe structure as applied to an inner shoe.

Figure 9 shows a one piece rubber overshoe upper, including vamp, shank and 15 counter portions.

Figure 10 shows the completed overshoe embodying the one piece upper of Figure 9, as applied to an inner shoe and with certain parts in section.

20 Figure 11 is an exterior view or elevation of the same.

Figure 12 is a section at 12—12 of Figure 11.

25 The rubber portion of the overshoe upper may be made of either one or two parts. Most of the novel or distinctive features of the rubber upper are embodied in the rear or counter portion of the upper. Figures 1 and 2 show the rear of counter upper member 30 C designed to co-operate with a front or vamp upper piece or member V, Figure 5, in a two piece upper construction, and Figure 9 shows a one piece rubber upper in flat or sheet form designated as a whole by 35 the reference character U and including rear or counter portions C' and a front or vamp portion V'. The two part rubber upper construction as exemplified in the embodiment of the invention shown in Figures 1 40 to 8 will first be described.

The rubber sheet or counter blank C, Figures 1 to 4, is preferably produced in substantially flat form and is so designed that it may be produced in a single operation 45 by suitable dies or rolls. It includes in the flat form, side members or wings 1 having edges 2 which are to form the top edges of the counter in the completed overshoe, these side or wing portions being connected by a 50 transverse portion 3, which forms the shank in the completed overshoe. The shank member 3 has a forward edge 4 usually of curved outline substantially as shown and the front ends of the wing portions 1 are defined by 55 edges 5, curved or suitably formed to co-operate with the vamp portion of the upper, presently to be described. The rear ends of the wing portions 1 are desirably formed with curved outlines 6, so designed that 60 when the counter member is properly placed or formed on a suitable last the rear portions of the wings will overlap substantially along the dotted lines 7 and the proper rear counter contour will be produced, as explained hereafter. Each side or wing por-

tion 1 is provided with a rib 8 which is generally curved substantially or approximately as shown, this rib beginning usually near the rear margin of the wing or substantially at the point of overlap indicated by the 70 dotted line 7 and extending in a curved line to a point near the rear edge of the shank portion 3. Preferably a rearward portion 8^a of each rib 8 projects on the inward face of the counter blank C, as shown 75 in Figure 2 and the forward portion 8^b of the rib projects on the outer surface of the blank as shown in full lines in Figure 1.

The counter blank has other edges 9 of suitable or curved contour, these edges merging with the rear edges 6 and also merging with a suitably curved rear edge 10 of the shank portion 3. The edge or margin 10 usually includes a central part 11 having a distinct bulge or rearward curvature for 80 purposes hereafter stated. Desirably the blank is thickened along the margins adjacent to the edges 9, this thickening constituting a reinforcement of the rubber blank around the heel opening. This thickening 85 may increase progressively toward the edges 9, and at those edges the material may be curved inwardly to provide portions 31 of angular cross section to cooperate with the heel of the inner shoe, in a manner explained 90 hereafter. As otherwise described, this feature of the invention consists in inwardly curving or bending the blank adjacent to the edges 9 which are to form the heel opening of the completed overshoe, and providing sharp edges or angles 13 which in the completed overshoe will closely fit the inner shoe counter and especially will fit in the joint or crevice between the shoe counter and the heel base and effectively exclude dirt 95 and moisture and also prevent any downward slipping of the overshoe counter. Desirably also, one or a plurality of parallel ribs 14 are provided along or adjacent to the edges 9, 10 and 11 as sufficiently shown 100 in Figures 1, 3 and 4. Desirably also wings 1 are thickened near their rearward ends. The increase in thickness may be gradual, and the thickened portions may correspond substantially to the lateral strips or zones 1^a, 110 Figures 1, 2 and 4, these being the portions of the rear ends of the counter wings which in the completed overshoe constitute the back or rear end of the counter, the two portions or zones 1^a adjoining each other along the lines 7 and being entirely free from the lining (later described) the rearward edges of which terminate along the dotted lines 23', Figures 1 and 2, in the completed overshoe. The zones or portions 1^a of increased 115 thickness, therefore, in this instance, are substantially defined by the dotted lines 7 and 23' in Figures 1 and 2. The thickening of the rear portions of the counter avoids the necessity for applying separate reinforce- 120

ments at the counter back, and also provides for ample resilient or elastic strength of the rear counter structure to retain the overshoe properly in position as more fully explained hereafter.

To the rear of the thickened zones 1^a, the counter wings 1 preferably have marginal portions or zones 1^b of reduced or moderate thickness, these zones being defined in Figures 1 and 2 by the dotted lines 7. These portions of reduced or moderate thickness are overlapped and adhesively secured when the counter blank is placed on a suitable last, as further described hereafter. The thickness of the material and its variations in cross sectional form or thickness are somewhat exaggerated in Figures 3 and 4 in order to explain these features clearly.

A vamp blank or rubber sheet V, Figure 5, is prepared in any suitable way to co-operate with the counter blank above described and a suitable lining L is also prepared, the front or vamp portion of which usually has the same contour as that of the rubber vamp V. The rear portions or wings 20 of the lining have edges 21 corresponding substantially to edges 2 of the counter blank and edges 22 corresponding substantially to edges 9 of the counter blank. The rear ends 30 of the lining wings are formed with a curved outline 23 corresponding substantially to the dotted lines 23' on the counter blank, as shown in Figures 1 and 2, these dotted lines indicating the location of the edges or margins 23 when the counter blank is positioned on the lining in process of manufacture, as hereafter explained. The lining also has lateral projections 25 arranged to meet or overlap and to underlie the shank portion 3 of the counter blank. The vamp blank V and the lining are formed with a suitably contoured edge or portion 26 intermediate the lining wings 20, this portion constituting the instep portion 27 of the completed overshoe.

The rubber vamp blank V is applied to the forward portion of the lining blank L with suitable adhesive, as shown in Figure 5, and then the combined lining and vamp blank are placed on a suitable last for the proper shaping and completion of the overshoe. Any suitable or ordinary last may be used in some cases but preferably a special last K, Figure 6, is provided to co-operate with the particular upper blanks preferably employed and especially with rear portions of the upper. For this purpose the rear end of the last has a depression or inset portion 28 which may include a substantially straight upper edge 29 and a lower incurved edge or portion 30, and substantially at the meeting point of these edges or portions a groove or channel 31 is provided extending around the back of the heel and along each side for a certain distance to accommodate

the ribs 8 or rib members 8^a. The combined lining and vamp blank are placed on the last, the forward portion of which may be of any ordinary or suitable shape. Usually a sole lining or insole 32 is placed on the bottom of the front portion of the last and the margins of the combined lining and vamp blank V are folded in under the insole or lining 32 and adhesively secured, and then the rubber sole 33 is applied with suitable adhesive, (Fig. 7). The shank members 25 of the lining are turned up against the insole or sole lining 32 and adhesively secured.

A rubber counter blank C is then applied to the last with its shank portion 3 underlying the shank of the insole, and the blank wings 1 are turned up against sides of the rear part of the last and over lining members of wings 20. The front margins adjacent to the lines 5 of the counter blank will then overlap the rear margins of the vamp blank substantially as indicated by lines 34, Figures 6 to 8. The rear ends of the blank wings 1 are pressed firmly around the back end of the last and their margins adjacent to the lines 6 are overlapped, the amount of overlapping being approximately indicated by the dotted lines 7, and these margins are adhesively secured. Rib members 8 are now located in rear portions of the last groove 31 and the rear part of the counter blank is formed to the shape of the last, or in other words, it has an incurve or depression 35 Figure 7, the deepest portion 36 of which is substantially at the point of meeting of the two rib members 8^a. The last with the fully formed overshoe upon it is then placed in a suitable vulcanizer and after vulcanizing, the overshoe is removed from the last and will then be in substantially the form shown in full lines in Figure 7.

When the completed overshoe is placed upon an inner shoe, as shown in Figure 8, the shoe heel projects through the heel opening 40 which is surrounded by the thickened and ribbed portion 14. The incurved edges 13 of the counter blank fit closely against the shoe counter and in the crevice between the counter and the heel base of the inner shoe; the rear curved portion 11 of the shank fits against the curved front face of the shoe heel and also fits snugly up against the shank of the shoe sole adjacent to its intersection with the heel. In this way moisture and dirt are effectively excluded.

By the described arrangement of the parts the rear counter portion of the overshoe as best shown in Figure 12 consists entirely of rubber, the fabric lining terminating along lines 23, and this rear wall of flexible rubber is normally conformed as shown in Figure 7, and when applied to the shoe is stretched rearwardly to conform to the shoe counter conformation as shown in

Figure 8, and exerts a yielding pressure against the shoe which firmly holds the rear counter portion of the overshoe in position and prevents downward displacement and equally well prevents upward displacement. The reinforcing ribs 8 moreover, extending all around the back of the overshoe counter and in curved lines down to the shank, exert additional tension for the same purpose, and the inwardly projecting members 8^a of these ribs located on the inner surface of the overshoe between the margins of the canvas lining bear very firmly against the top edge of the inner shoe counter and additionally prevent slipping.

The rear marginal portions 1^b overlapped and secured as described, retain the rear ends of rib members 8^a substantially in contact with each other, producing a practically continuous integral inner retaining bead which grips the top edge of the inner shoe counter and retains the rear end of the overshoe counter in position. The forward portions of the continuous ribs, that is to say, the portions 8^b, are formed on the outer surfaces of the blank and the inner surfaces of the blank along the sides of the counter are smooth, to facilitate the entrance of the inner shoe and so that the internal rib or bead 8^a is readily positioned at the upper edge of the shoe counter simultaneously with the positioning of the depressed portion 36 of the overshoe counter at the rear of the shoe counter. The external rib portions 8^b assist materially in stiffening and holding the sides of the soft overshoe counter in an upright position while the overshoe is being applied.

While the rear shape of the overshoe may vary considerably, while conforming to the general principles above explained, the particular shape shown is preferred in many cases. In this preferred arrangement the upper portion 42 of the rear end of the overshoe counter is directed or flared backward and this conformation facilitates the application of the overshoe to the inner shoe and also tends to relieve the tension on the shoe and the foot of the wearer when the overshoe is applied, the greater tension being exerted below the upper edge of the overshoe or against a stiff portion of the inner shoe counter.

Suitable edges of the vamp and counter blanks may be provided with beads or ribs such as 45 and 46 so that in the completed overshoe these ribs run around the entire upper periphery.

Figures 9, 10 and 11 show a modified structure in which the rubber overshoe upper is made in a single blank U including a vamp portion V' and counter wing portions C. In this case the counter portions or wings have shank extensions 50 arranged to overlap substantially as indicated by

dotted lines 51. This unitary blank and especially its rear portion may have any or all of the improvements or characteristic features of the counter construction previously described, these elements being designated by similar numerals. The unitary upper blank is applied to a suitable lining which may be of the same shape as shown in Figure 5, the rear edges 23 of the lining being located as indicated by dotted lines in Figure 9. When the upper blank is adhesively applied to the lining the combined materials are placed on the last and the bottom margins of the vamp portion V' are turned in and secured to the inner sole, the counter portions or wings are formed about the counter of the last and the rear margins adjacent to the lines 6 are overlapped as in the previous instance, and the shank members 50 are turned in, overlapped and adhesively secured, and the properly shaped overshoe is then vulcanized on the last, producing a complete overshoe which will in normal shape have the same formation as shown in Figure 7 with the exception that the "upper" is in one piece instead of two.

I claim:

1. An upper blank for overshoe construction consisting of a substantially flat sheet of rubber or rubber composition including spaced counter members or wings having curved rear margins, the curvatures of which provide an elastic retaining depression when connected together, and provided with integral thickened and ribbed marginal portions adjacent to certain of their longitudinal edges, said counter wings also having curved reinforcing ribs.

2. A heelless overshoe upper structure comprising a vamp and counter portions, the counter portion having a heel opening to substantially conform to the outline of a shoe heel seat, and being provided with a thickened ribbed margin about said heel opening, the upper structure also having a shank portion, the rear margin of which is convexly curved and upwardly deflected to conform to the shoe heel and the shoe shank adjacent the heel.

3. An overshoe having an opening for the heel of the inner shoe and having a plurality of reinforcing beads extending along the edge of said opening, said opening having a reinforced shank at said edge of said opening and a rib formed on the inner side of the counter of said overshoe adapted to engage over the counter of the inner shoe intermediate the height of the counter and extending forwardly and downwardly to a point near said shank.

4. A heelless overshoe having a heel opening at the rear end thereof and having a concavely depressed elastic part more extensible than the body of said overshoe extending upwardly from a point adjacent the rear

edge of said heel opening toward the upper edge of the counter of said overshoe and exerting tension in the overshoe and at the edge of said opening.

5. A heelless overshoe having a heel opening at the rear thereof and having a concavely depressed elastic part more extensible than the body of said overshoe extending upwardly from a point adjacent the rear edge of said heel opening toward the upper edge of the counter of said overshoe and exerting tension in the overshoe and at the edge of said opening, said overshoe having a lining with a gap formed therein at said

15 elastic portion.

6. A rubber overshoe comprising a lined vamp and an unlined counter portion and having an elastic edged heel opening, the rear end of the counter portion being formed with a depression intermediate its upper and lower edges, the counter above the depression being flared backward, said unlined and elastic counter depression serving to exert a resilient pull upon the shoe counter to

25 retain the heel opening margin closely about the heel near the top thereof.

7. A rubber overshoe comprising a lined vamp and an unlined counter portion and having an elastic edged heel opening, the rear end of the counter portion being formed with a depression intermediate its upper and lower edges, the counter above the depression being flared backward, said unlined and elastic counter depression serving to exert

35 a resilient pull upon the shoe counter to retain the heel opening margin closely about

the heel near the top thereof and to maintain the shank edge at the front of the heel opening closely against the front of the shoe heel where it joins the shoe shank.

40

8. A rubber overshoe comprising a lined vamp and an unlined elastic counter portion, the rear end of the counter portion being formed with a depression located substantially below its upper edge, the counter above the depression being flared backward, said unlined and elastic counter depression serving to exert a resilient pull upon the shoe counter to retain the overshoe and especially rear parts thereof in proper position upon

45

50

the shoe.

55

9. A heelless overshoe, including an unlined elastic counter and an elastic heel opening at the rear lower margin thereof, said margin having a thickened reenforcement and a sharp edge at its inner face and being incurved and adapted to be outwardly displaced to elastically and powerfully cling to the heel seat of an inner shoe and form a tight waterproof seal.

60

10. An overshoe having a heel opening defined by a thickened, reenforced, sharp elastic edge formed with an inward curl, said curled edge being adapted to be displaced outwardly and to cling tightly and adjustably about the heel seat of an inner shoe.

65

Signed at New York in the county of Bronx and State of New York this 10th day of May A. D. 1923.

70

PETER H. MARGULIS.
